SHOE MANUFACTURE

Robert H. Lawson, Beverly, Mass., assignor to
 United Shoe Machinery Corporation, Paterson, N. J., a corporation of New Jersey

Application February 1, 1935, Serial No. 4,544

2 Claims. (Cl. 12—145)

The present invention relates to shoe manufacture and is herein illustrated in its application to the assembling of shoe upper parts, including a non-molded counter, upon a last.

5 In the manufacture of shoes provided with non-molded counters, it is desirable to temper the counter thoroughly before assembling the shoe upper parts upon a last in order that the counter may readily conform to the shape of the heel 10 end of the last and also to put the counter into a condition in which its everlasting margin will readily fold over the margin of the insole. A non-molded counter which is in perfect temper for the assembling operation has a considerable 15 amount of moisture therein and consequently when the counter is inserted between the lining and the upper and pressure is applied to shape the counter to the last moisture from the counter passes through the lining and into the insole 20 thereby softening the margin of the insole to such an extent that it cannot resist the force applied to the margin of the counter to lay it over the insole and as a result the edge face of the insole is rounded or otherwise misshaped. The margin 25 of the insole having been thus misshaped in the assembling operation, it is impossible in the subsequent operations upon the heel end of the shoe to produce a heel seat having a well defined margin such as is required of high grade footwear. 30 As a consequence of this undesirable feature of non-molded counters, it has become a usual practice in shoe manufacture to shape the counter and form an inturned flange in its bottom margin before assembling the counter in a shoe. 35 Such counters are not in temper when they are assembled in their shoes and if they do not register accurately with the heel end of the last, as is often the case, it is very difficult to locate the counter in the desired position and to prevent 40 displacement of the counter in, for example, the pulling-over operation.

It is an object of the present invention to overcome the above-mentioned objection to the use of non-molded counters while retaining the desirable features of non-molded counters in the manufacture of footwear of high quality.

With the above object in view, the present invention consists in lasting the margin of a shoe lining over and upon a marginal plate on an insole, said plate being herein illustrated as a heel plate the outer edge of which is arranged to coincide with the edge face of the heel portion of the insole, impaling the margin of the lining on points projecting upwardly from the insole and 50 preferably formed in the plate, positioning a shoe 55

stiffener, for example a non-molded counter, with its sole margin arranged to be lasted over said plate, impaling the margin of said stiffener on said points, then clenching the points against the stiffener, and thereafter lasting the margin of the upper over upon said stiffener, for example, in a heel seat lasting machine.

The invention will appear more fully from the following description when read in connection with the accompanying drawing and will be 10 pointed out in the appended claims.

In the drawing,

Fig. 1 is a perspective view of a heel plate embodying features of the present invention;

Fig. 2 is a perspective view of the heel end of 15 an insole provided with a heel plate such as that illustrated in Fig. 1;

Fig. 3 is a perspective view of an upper assembled on a last having an insole such as that illustrated in Fig. 2 attached to its bottom face, the 20 overlasted margin at the heel end of the lining having been impaled upon points on the heel plate;

Fig. 4 is a perspective view of the heel end of an 25 assembled upper illustrating particularly the operation of assembling a counter in the shoe and securing it to the insole; and

Fig. 5 is a perspective view similar to Fig. 2 illustrating an alternative construction.

Referring now to Fig. 1, the numeral 10 indicates a metal heel plate which, as herein illustrated, is a narrow strip having the curvature of the edge face of the heel end of an insole. The plate 10 is provided with points 12 extending downwardly from the inner edge face of the plate in order to provide means for permanently securing the plate to the heel end of an insole. Preferably three such points are provided, one at each end of the plate and one substantially midway between its ends. When the plate 10 is properly secured to an insole 14 of like size, as illustrated in Fig. 2, the outer edge face 16 of the plate is arranged to coincide with the edge face 18 of the insole. The plate 10 is provided with a series of impaling points 20 arranged to extend upwardly from the inner edge face of the plate for the reception of the overlasting margins of shoe upper parts, for example, a lining 22 and a non-molded counter 24 illustrated in Fig. 4. The impaling points 20 are readily bendable, thus permitting them to be clenched against the overlasted margins of shoe upper materials in order to hold them in overlasted position, as illustrated at 26 in Fig. 4. In order to insure that the points 20 will not interfere with the driving of heel seat 50 55

lasting tacks, the heel plate 10 is made as narrow as practicable, thereby permitting the points 20 to be located between the edge face of the insole and the region of the insole which, at a later 5 stage in the manufacture of the shoe, receives the heel seat lasting tacks.

Referring now to Fig. 5 illustrating an alternative insole construction, a heel plate 38 which is identical to the heel plate 10 except that it is not 10 provided with impaling points 20 is permanently secured to an insole 40 by points 42 similar to the points 12 of the plate 10. Impaling points 44 which are separate and distinct from the plate 38 project from the bottom face of the insole between 15 the inner edge face of the plate 38 and the area which is to receive the heel seat lasting tacks.

One method of making shoes in accordance with the present invention consists in attaching to a last bottom an insole the heel end of which is 20 provided with the heel plate of the present invention, positioning the heel ends of shoe upper materials relatively to a last 28, and temporarily attaching them thereto, for example by driving a tack 30 through the upper in the region of the 25 back seam and into the last. The last 28 with the upper thereon is then supported, for example on a bench spindle 32 (Fig. 4). The lining 22 at its heel end is then drawn upwardly to pull out any wrinkles that may have formed therein. 30 Hand pincers may be employed for this operation. If desired, a heel band may be provided such, for example, as the heel band commonly employed in bed lasting machines, such heel band serving to hold the lining in position after the operator 35 has pulled it up with his hand pincers. After the operator has positioned the lining to his satisfaction the margin of the lining extending above the insole is laid over the margin of the insole and impaled upon the points 20 of the heel plate. 40 The operator now positions the wings of the non-molded counter 24 to his satisfaction and then lays the margin of the counter extending above the overlasted margin of the lining upon the shoe bottom. The counter, of course, has been tempered 45 to put it in condition for the assembling and lasting operations. The overlasting margin of

the counter 24 is now impaled upon the points 20 of the heel plate. In impaling a counter upon said points it has been found desirable to employ a hammer and a tool such, for example, as the tool 34 illustrated in Fig. 4 which has a cavity 36 5 formed in its work engaging end to provide clearance for the point 20 as the counter is forcibly impaled thereupon. After impaling the margin of the counter upon the points 20 said points are bent over and pounded down against the margin 10 of the counter, as illustrated at 26 in Fig. 4.

While the invention has been illustrated and described in its application to the assembling of shoe parts, including a non-molded counter, upon a last, it is to be understood that the invention is 15 not thus limited in its scope but is applicable to the assembling of shoe upper parts including a molded counter or to the assembling of shoe uppers provided with no counter whatever.

Having thus described my invention, what I 20 claim as new and desire to secure by Letters Patent of the United States is:

1. That method of making shoes which comprises lasting the margin of a shoe lining over and upon a marginal plate on an insole, impaling said margin on points projecting upwardly from the insole, positioning a shoe stiffener with its sole margin arranged to overlie said plate, impaling the margin of said stiffener on said points, 25 clenching said points against the margin of said stiffener, and thereafter lasting the margin of the upper over upon said stiffener. 30

2. That method of making shoes which consists in lasting the sole margin of the heel portion of a lining over and upon a marginal plate 35 on the heel portion of an insole, impaling the margin of the lining upon points projecting from the insole, lasting a non-molded counter over and upon the lasted margin of the lining, impaling the sole margin of the counter upon said impaling points, 40 clenching said points against the margin of the counter, and thereafter lasting the sole margin of the upper over upon the lasted margin of the counter. 45

ROBERT H. LAWSON.
